DESIGN FOR A WALKING BEAM

Walter C. Trout, Lufkin, Tex., assignor to Lufkin
Foundry & Machine Company, Lufkin, Tex., a
corporation

Application February 1, 1937, Serial No. 67,379

Term of patent 14 years

To all whom it may concern:

Be it known that I, Walter C. Trout, a citizen
of the United States, residing at Lufkin, in the
county of Angelina and State of Texas, have in-
vented a new, original, and ornamental Design
for a Walking Beam, of which the following is a
specification, reference being had to the accom-
panying drawing, forming part thereof.

Fig. 1 is a side elevation of a walking beam
showing my new design;

Fig. 2 is an end elevation thereof showing the
design.

I claim:

The ornamental design for a walking beam as
shown.

WALTER C. TROUT.
